(57) **CLAIM**

The ornamental design for a ball carrier, as shown and described.

DESCRIPTION

FIG. 1 is a top front right perspective view of the ball carrier, showing my new design, with the top rear right perspective view being a mirror image thereof;

FIG. 2 is a front elevation view thereof, with the rear elevation view being a mirror image thereof;

FIG. 3 is a right side elevation view thereof, with the left side elevation view being a mirror image thereof;

FIG. 4 is a top plan view thereof;

FIG. 5 is a bottom plan view thereof; and,

FIG. 6 is a top front right perspective view thereof, shown in use with a sports ball.

The broken lines shown in the FIG. 6 depict a sports ball that is environment and forms no part of the claimed design.

Any portion of the design not shown in the drawings forms no part of the claimed design and is hereby disclaimed.
